US0D1038560S

(12) **United States Design Patent** (10) **Patent No.:** **US D1,038,560 S**
 Spraw et al. (45) **Date of Patent:** **** Aug. 6, 2024**

(54) **LUG CLEANING APPLICATOR WITH CONTAINER**

(71) Applicants: **Sydney E. Spraw**, Holland, OH (US);
Billy Joe Hesser, Sylvania, OH (US);
Jeffrey Hendrzak, Holland, OH (US);
Wyatt Yenor, Jerome, MI (US)

(72) Inventors: **Sydney E. Spraw**, Holland, OH (US);
Billy Joe Hesser, Sylvania, OH (US);
Jeffrey Hendrzak, Holland, OH (US);
Wyatt Yenor, Jerome, MI (US)

(73) Assignee: **Designtechs, Inc.**, Holland, OH (US)

(**) Term: **15 Years**

(21) Appl. No.: **29/828,531**

(22) Filed: **Feb. 27, 2022**

(51) LOC (14) Cl. **07-05**

(52) U.S. Cl.

USPC **D32/35**
